US0D1093011S

(12) **United States Design Patent** (10) **Patent No.:** **US D1,093,011 S**
(45) **Date of Patent:** **** Sep. 16, 2025**

(54) **SOAP DISPENSER BRACKET ASSEMBLY**

(71) Applicant: **Spartan Chemical Company, Inc.**,
Maumee, OH (US)

(72) Inventors: **Prasanna Natarajan**, Wixom, MI (US);
Grey Parker, West Bloomfield, MI (US); **Daniel Genord**, South Lyon, MI (US); **William J. Schalitz**, Swanton, OH (US)

(73) Assignee: **SPARTAN CHEMICAL COMPANY, INC.**, Maumee, OH (US)

(**) Term: **15 Years**

(21) Appl. No.: **29/810,551**

(22) Filed: **Oct. 6, 2021**

(51) LOC (15) Cl. **23-08**

(52) U.S. Cl.

USPC **D6/545**

(57) **CLAIM**

The ornamental design for a soap dispenser bracket assembly, as shown and described.

DESCRIPTION

FIG. 1 is a front perspective view of the new design for a soap dispenser bracket assembly;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

Portions of the soap dispenser bracket assembly shown in broken lines form no part of the claimed design.

1 Claim, 7 Drawing Sheets
